UNITED STATES PATENT OFFICE.

WILLIAM O. GARBER, OF SOUTH RICHMOND, VIRGINIA.

AUTOMATIC GAS-VALVE.

1,058,046.

Specification of Letters Patent.

Patented Apr. 8, 1913.

Application filed December 14, 1911. Serial No. 665,793.

To all whom it may concern:

Be it known that I, WILLIAM O. GARBER, citizen of the United States, residing at South Richmond, in the county of Chesterfield and State of Virginia, have invented 5 certain new and useful Improvements in Automatic Gas-Valves, of which the following is a specification.

This invention relates to automatic gas 10 valves, and more particularly to that type which are designed to close automatically should the flame be accidentally extinguished, or should there be a reduction in pressure so considerable as to practically 15 extinguish the flame.

The valve, as in the case of other valves of this type, includes a thermostatic element, and the invention contemplates so locating and arranging this element with respect to 20 the burner that the flame will not be distorted, and the support for the thermostatic element will not be so located as to collect soot from the burner flame.

A further aim of the invention is to provide 25 an automatic gas valve of the type mentioned which will be positive in its automatic closing movement, and in which the valve itself is in direct alinement with the thermostatic element so that expansion and 30 contraction of the element will act directly to open or close the valve, the employment of intermediate connections and of the usual rotary plug valve and operating spring therefor, being obviated.

35 For a full understanding of the invention reference is to be had to the following description and accompanying drawing, in which:—

Figure 1 is a perspective view of the device 40 embodying the present invention. Fig. 2 is a vertical sectional view therethrough taken in a plane from front to rear. Fig. 3 is a group perspective view illustrating the valve of the device.

45 Corresponding and like parts are referred to in the following description and indicated in all the views of the accompanying drawing by the same reference characters.

In the drawing the feed-tube of the device 50 is indicated by the numeral 1 and is interiorly threaded at its lower end as at 2 for connection with the ordinary gas bracket, or similar gas supply pipe. For a purpose to be presently explained, this burner tube is interiorly threaded at its upper end as at 3 and connecting its threaded

portions is a bore 4 which is of less diameter than the tube at either end.

The burner tube is indicated by the numeral 5 and has fitted in its upper end the 60 usual burner tip 6, and at its lower end this burner tube is threaded onto the upstanding arm 7 of an elbow 8, which has its other arm threaded as at 9 into one side of the tube 1. This elbow has the usual gas passage 10 which communicates at one end with the bore 4 and at its other end with the burner tube 5. A pilot tube 11 is fitted at its lower end in an opening 12 formed in the angle of the elbow 8, and this tube extends up between the feed-tube 1 and the burner tube 5, as shown in Figs. 1 and 2 of the drawing and serves a purpose to be presently explained.

The feed-tube 1 is formed interiorly, at 75 the lower end of its bore 4, with a valve-seat 13, against which rests the head 14 of a valve, the stem of which is indicated by the numeral 15 and is flattened as at 16. This stem projects up into the bore 4, and when 80 the valve is away from its seat, gas may flow around the head 14 thereof and between the flattened sides of the stem and the wall of the bore and out through the passage 10 to the burner tube 5. The valve 14 is normally 85 held to its seat 13 by means of a spring 17 which bears at its upper end against the underside of the said head and at its lower end fits in a seat 18 formed in a threaded plug 19 removably and adjustably fitted in 90 the lower threaded end of the feed-tube 1. The feed-tube 1 is also formed interiorly at the upper end of its bore 4 with a valve-seat 20 upon which is adapted to rest a head 21 formed at the upper end of a stem 22 which 95 is slidably fitted in the bore 4. This head 21 serves as a support for the thermostatic element, as will be presently explained, and also serves the purpose of a valve to close the upper end of the bore 4 in a gas-tight 100 manner when the valve 14 is open. The lower end of the stem 22 rests upon the upper end of the stem 15 of the valve 14, and when the valve 14 is in closed position, the head 21 will be in spaced relation to the 105 seat 20.

The thermostatic element is supported in a frame which includes a lower threaded head 23 which is threaded into the upper end of the tube 1 in the manner illustrated 110 in Fig. 2 of the drawing, an upper head 24, and outwardly, oppositely bowed con-

necting portions 25 which extend between the two heads. The head 23 is formed axially with an opening 26, and the head 24 is interiorly threaded as at 27 and has fitted into it the base 28 of a bracket including spaced ears 29, the said base being formed with an opening 30.

- The thermostatic element of the valve is indicated by the numeral 31 and is in the nature of a solid rod of brass or other material having the property of expanding and contracting to a considerable degree when subjected to temperature changes. This rod 31 is fitted at its lower end through the opening 26 in the head 23 and rests in a seat 32 formed in the head 21 and at its upper end fits into the opening 30 in the bracket base 28.
- 10 15 20 25

By referring to Figs. 1 and 2 of the drawing it will be observed that the upper or discharge end of the pilot tube 11 is presented directly toward the thermostatic rod 31 and is but slightly spaced therefrom at a point substantially midway between its ends.

To provide for manual opening of the valve 14, there is mounted through the ears 29, for oscillation, the stem 33 of a finger-key 34, this stem being squared between its ends and having fitted upon its squared portion a rocker 35 having a shoulder 36 formed upon its under edge. The rocker is, of course, confined between the ears 29 and projects forwardly above the base of the bracket 30 and bears at its forward end against the upper end of a plug 37 fitting within the opening 30 and resting upon the upper end of the thermostatic rod 31.

The operation of the valve is as follows:—

40 It will be understood that normally the valve 14 is held closed by means of a spring 17, the thermostatic rod 31 being at such time in contracted condition. When it is desired to light the burner, the finger-key 34 is turned 45 so as to swing down the forward end of the rocker 35, thereby depressing the thermostatic rod 31 and the valve 14 through the medium of the supporting element 21 upon which the lower end of the thermostatic rod 50 rests. Gas will then pass through an opening 38 which is formed in the plug 19, and will flow around the valve 14 and up through the bore 4 and passage 10 into the pilot tube 11. The gas is ignited at the discharge end of the 55 pilot tube and the thermostatic rod 31 is rapidly heated, and in a few seconds will expand to such degree as to press upwardly against the rocker 35 until the shoulder 36 engages with the base of the bracket 28 and 60 prevents further upward swinging movement of the rocker and against the head 23 so as to hold the same against the seat 20 and hold the valve 14 in open position. The gas is then ignited at the burner tip 6. 65 Should the flame become accidentally ex-

tinguished, or should the gas pressure be so lowered as to practically extinguish the flame, the thermostatic rod 31 will contract, thereby allowing the spring 17 to force the valve 14 against its seat 13 and in this manner the supply of gas to the burner tube will be cut off until the valve is again manually opened.

It will be understood that the supporting element including the head 32 and stem 22 is in effect a part of the valve 14, the stem of the valve and the stem 22 of the said supporting element having their ends abutting, but being disconnected so that both elements may be removed from the feed-tube.

80 85 90

The plug 37 is preferably of resilient material and is split, as shown in Fig. 2 of the drawing, whereby it will fit frictionally in the opening 30 and will consequently remain in lowered position until shoved upwardly by the expansion of the thermostatic rod 31.

Having thus described the invention what is claimed as new is:—

1. In an automatic gas valve, a feed tube provided interiorly with a valve-seat, a valve arranged within the tube and normally held against the seat, a burner tube leading from the feed tube, a thermostatic element arranged in juxtaposition to the burner tube and bearing against the valve and arranged, upon expansion to move the valve to open position, and a manually operable rocker arranged for actuation to depress the thermostatic element and move the valve to open position.

95 100 105 110 115 120

2. In an automatic gas valve, a feed tube provided interiorly with a valve-seat, a valve arranged within the tube and normally held against the seat, a burner tube leading from the feed-tube, a support extending above the feed-tube, a thermostatic rod bearing at its lower end against the valve, a finger-key mounted at the upper end of the support for oscillation, a rocker carried by the finger-key and arranged, when the key is turned in one direction, to bear against the rod and force the same downwardly to open the valve, the said rocker having an abutment co-operating with the support to limit its rocking movement in an opposite direction whereby oscillation of the rocker in such direction through the expansion of the thermostatic rod is limited.

125 130

3. In an automatic gas valve, a feed-tube provided interiorly with a valve seat, a valve arranged within the tube and normally held against the seat, a burner tube leading from the feed-tube, a thermostatic element arranged adjacent to the burner tube and bearing directly against the stem of the valve, a rotatable abutment for the other end of the thermostatic element, and means whereby the said abutment may be rotated to move the thermostatic element bodily in a direction to open the valve.

4. In an automatic gas valve, a feed-tube provided interiorly with a valve-seat, a valve arranged within the tube and normally held against the seat, a support mounted upon the feed-tube, a thermostatic element slidably mounted on the support and bearing at one end against the valve, a burner-tube leading from the feed-tube and located adjacent to the said thermostatic element, and means whereby the said thermostatic element may be slid bodily in a direction to open the valve.
5. In an automatic gas valve, a feed-tube provided interiorly with a valve-seat, a valve arranged within the tube and normally held against the seat, a support mounted upon the feed-tube, a thermostatic element slidably mounted on the support and bearing at one end against the valve, a burner-tube leading from the feed-tube and located adjacent to the said thermostatic element, and means whereby the said thermostatic element may be slid bodily in a direction to open the valve.

4. In an automatic gas valve, a feed-tube provided interiorly with a valve-seat, a valve arranged within the tube and normally held against the seat, a support mounted upon the feed-tube, a thermostatic element slidably mounted on the support and bearing at one end against the valve, a burner-tube leading from the feed-tube and located adjacent to the said thermostatic element, and means whereby the said thermostatic element may be slid bodily in a direction to open the valve.
5. In an automatic gas valve, a feed-tube provided interiorly with a valve-seat, a valve arranged within the tube and normally held against the seat, a support mounted upon the feed-tube, a thermostatic element slidably mounted on the support and bearing at one end against the valve, a burner-tube leading from the feed-tube and located adjacent to the said thermostatic element, and means whereby the said thermostatic element may be slid bodily in a direction to open the valve.
- 20
- 25

mounted on the support and bearing at one end against the valve, a burner-tube leading from the feed-tube and located adjacent to the said thermostatic element, and means whereby the said thermostatic element may be slid bodily in a direction to open the valve, said means comprising an abutment mounted for oscillation upon the support and engaged by the other ends of the thermostatic element.

In testimony whereof I affix my signature in presence of two witnesses.
